ATTORNEY

UNITED STATES PATENT OFFICE

MELDA C. DU BOIS, OF SAN FRANCISCO, CALIFORNIA

SUNSHADE

Application filed March 14, 1932. Serial No. 598,733.

The present invention relates particularly to means for protecting the human face from the direct and indirect glaring rays of the sun, and the wind.

5 It is one object of the present invention to provide a means of the character indicated that will give the desired protection and yet permit free circulation of air over the face whereby to permit free breathing of fresh 10 air and prevent undue heating through the formation of air pockets.

It is another object of the invention to provide a means of the character indicated that will provide positive protection to the 15 forehead of the wearer.

It is still another object to provide a means of the character indicated that will be adaptable to heads of various sizes, that will be light in weight, easily and quickly 20 applied and removed, strong, durable, economical to manufacture, that will permit unobstructed vision in all directions, and that will be highly efficient in its practical application.

25 In the drawing:

Figure 1 is a perspective view of a device embodying my invention in position on the head.

Figure 2 is a sectional view through that 30 portion of the device overlying the forehead.

In the particular embodiment of the invention as herein disclosed I show at 1 an endless elastic band adapted to entirely encircle the head just above the eyebrows and 35 of sufficient width to cover a material portion of the forehead. An elastic band 2 is fastened to the upper edge of band 1 at the front and back as indicated at 3 and 4 respectively and is adapted to pass from front 40 to back over the top of the head. Another elastic band 5 is fastened to the two sides of band 1 as at 6 and 7 and to the center of band 2 as at 8, bands 2 and 5 serving to support band 1 in the desired position as 45 indicated.

At 9 is shown a wide elastic band secured at its lower edge to the upper edge of band 1 at point 3 and passes rearwardly and downwardly from both sides thereof to the points 50 of attachment of band 5 to band 1 at 6 and 7.

At 10 is shown a transparent sheet of suitable flexible and transparent material, such as celluloid provided with an edging 11. This sheet may be of any desired conformation and is attached to band 1 at the upper 55 ends of its side edges as shown at 12 and 13, the upper edge 14 of the shield being of greater length than that of the band 1 between the points of attachment whereby to form an open space at 15.

The shield 10 is here shown as stitched to the band 1 at 12 and 13 in such a manner that it is supported at right angles to the plane of the band when in position on the head, pulling the band down at the back 65 of the head serving to throw the lower portion of the shield forwardly in such a manner as not to bear against the nose of the wearer.

By means of this construction air is allowed to circulate freely over the face of the wearer since the shield has no positive contact with the face at any point, ample space being provided at 15 to permit the air to flow freely therethrough. Since the 70 upper edge 14 of the shield is held away from the forehead, the forehead is not fully protected thereby therefore I provide a means, including band 1 and band 9, to directly overlie the forehead and protect it 75 from the direct rays of the sun.

While the whole shield in the present case is described as being made of celluloid, it is obvious that similar results may be obtained if only a portion, particularly the upper 80 portion, or top edge portion, be formed or constructed in such a manner as to be resilient. With a flexible but non-resilient band 1 and a resilient shield the device may be collapsed and rolled up into a very small 85 compact package for transportation, but when in position on the head the positioning of the band 1 automatically bows the shield, thrusting the central part forwardly and causing the side edges to fit closely against the side of the head.

It is to be understood, of course, that while I have herein shown and described but one specific embodiment of the invention, changes in form, construction, and method 90 95 100

of assembly and operation may be made within the scope of the appended claim.

I claim:

A device of the character described comprising a head band of elastic material, a pair of cross bands arranged at right angles to each other and having their ends attached to the front and rear portions and the side portions respectively of said head band, a second band associated with the front portion of said head band and having its ends coincident with said head band and fastened thereto at the points of the latter's attachment to the laterally extending cross band, said second named band extending upwardly intermediate its ends to cover the forehead of the wearer and having the lower edge of its central portion fastened to the upper edge of said head band at the point of the latter's attachment to said forwardly extending cross band, and a resilient sheet of transparent material substantially rectangular in shape fastened at its upper corners to said head band, said sheet being of a width greater than the portion of the head band confined between the points of attachment thereto to space said sheet from the face of the wearer.
